H. ADELMANN

CORNED BEEF COOKER

Filed June 4, 1923.

INVENTOR
Hans Adelmann
BY
G. H. Beeler
ATTORNEY

UNITED STATES PATENT OFFICE.

HANS ADELMANN, OF NEW YORK, N. Y., ASSIGNOR TO HAM BOILER CORPORATION, OF NEW YORK, N. Y., A CORPORATION OF NEW YORK.

CORNED-BEEF COOKER.

Application filed June 4, 1923. Serial No. 643,376.

To all whom it may concern:

Be it known that I, HANS ADELMANN, a citizen of the United States, residing at New York city, borough of the Bronx, in the 5 county of Bronx and State of New York, have invented certain new and useful Improvements in Corned-Beef Cookers, of which the following is a specification.

This invention relates to that type of 10 appliances known as meat cookers or ham boilers and has special reference to that species of such machines as are now recognized under the term corned beef cookers in which the body is oblong rectangular and 15 relatively wide in proportion to its depth and provided with a longitudinal partition.

Among the objects of the invention is to 20 provide a corned beef cooker with a fixed rigidly connected partition in the longitudinal center of the receptacle and whose cover, movable downward toward the bottom of the receptacle for pressing the commodity while being cooked, is provided also with a partition meeting or overlapping the 25 body partition.

Another object of this invention is to improve the construction of the receptacle with 30 reference to the material from which it is made and adapting such material for co-operation with rack-like fasteners pivotally connected to a cross bar attached resiliently to the cover.

With the foregoing and other objects in view the invention consists in the arrangement and combination of parts hereinafter 35 described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a plan view.

45 Fig. 2 is a vertical longitudinal section on the line 2—2 of Fig. 1.

Fig. 3 is a vertical transverse section on the line 3—3 of Fig. 1.

50 Fig. 4 is a fragmentary detail of the locking mechanism for the cover.

Referring now more specifically to the drawings the receptacle 10 is of substantially rectangular form in plan and having side and end walls approximately vertical, the

bottom being closed and the open top being 55 surrounded with a flange 11 projecting outward in a horizontal plane except at the centers of the ends where they are bent downward forming engagement lips 12. The receptacle is formed of any suitable 60 relatively thin material such as metal and is fitted along its longitudinal center with a vertical partition 13 whose upper edge is straight and lies along a plane somewhat or close above the vertical center of the receptacle. Thus the receptacle is sub-divided into two equal portions or cavities into which relatively long strips or pieces of corned beef, tongues, or other commodities to be cooked, may be placed and later subjected to compression while being cooked.

The cover 14 is mainly flat and is provided with a downwardly projecting reinforcement or finishing flange 15 adapted to move close down along the inner surface of 75 the sides and ends of the receptacle. This cover also may be constructed of any suitable relatively thin metal and has formed as an integral part thereof a downwardly projecting partition 16. This partition is 80 straight and flat and rigid and is designed to co-operate with the receptacle partition 13 when the cover is inserted and moved downward toward the partition 13. The vertical width of the partition 16 is such 85 that it preferably overlaps the upper portion of the partition 13 in practice. Hence the partition 16 is formed slightly offset from the longitudinal center of the cover so that the lower edge of the partition 16 will 90 pass the upper edge of the partition 13 on either side irrespective of how the cover is introduced into the receptacle. After the receptacle is suitably filled or supplied with the commodities to be cooked and the cover is put into place, the contents of the two sides of the receptacle will be formed into two substantially equal rectangular masses, the cover partition though offset from the 95 center being so relatively thin will hardly be noticeable in the finished commodity. In

other words, the two portions of cooked meat or the like will be practically the same size and shape. Moreover, the manner of forming or pressing these contents, including the partition extending downward from the cover, provides a means for facilitating the delivery of the meat masses from the 100 105

receptacle after the cover is withdrawn. That is to say, considering the cover and especially its partition as a wedge in its relation to the meat masses, when the wedge 5 is withdrawn the contents of the receptacle are relieved in respect to the receptacle walls and hence slip the more freely therefrom when the receptacle is inverted. Moreover, the free edge portions of the partitions 13 10 and 16 are beveled and tapered and formed relatively sharp, both to facilitate assemblage of the parts and to emphasize the wedge effect just described. It will be appreciated also that the mass cooked and 15 molded in the compartment into which the partition 16 projects will be relieved directly by the withdrawal of the partition 16 and hence will be delivered from the receptacle easier and quicker than the mass from 20 the other compartment, a matter of considerable importance if it be desired to keep the two masses separate.

Attached resiliently to the cover 14 is a handle or bar 17 of double cross formation 25 or comprising a relatively straight central portion having off shoots or arms 17' adjacent to each end and through which are projected upward loosely a like number of fasteners such as bolts or screws 18 which 30 are secured into bosses 19 formed on the upper surface of the cover. The extreme ends of the bar 17 are turned or rolled into knuckles 20. A coil spring or cushion 21 surrounds each bolt 18 between the cover 35 and the adjacent arm 17'. By providing these lateral extensions or arms of the bar 17 and laterally spaced pair of springs 21, the cover is more steadily guided in its compressing action than would otherwise be 40 true, taking into consideration the relative width of the receptacle and the fact that the two sides thereof are or may be filled independently or unequally.

Suspended from a horizontal pivot pin 45 22 extending through the knuckle 20 at each end of the bar 17 is a rack-like fastener 23. Each of these racks is formed at its upper end with knuckles 24 between which is aligned the knuckle 20. The fasteners 23 may be variously constructed, but 50 preferably as shown they are of sheet metal, portions of which are struck inward along the vertical center forming teeth 25 for co-operation severally with the adjacent lip 12 55 of the rim of the receptacle. These teeth 25 are thus freely and cheaply formed and they have strong co-operative relation with the lips in practice. Moreover, the fasteners 23 have smooth outlines and are freely 60 manipulated.

The operation of the device will be readily understood, for after the receptacle is filled as above described and the cover is inserted and the partitions 13 and 16 meet 65 or overlap according to the fulness of the

receptacle, the operator will bear downward upon the ends of the bar 17, placing the contents of the receptacle under sufficient compression and he will then cause the engagement between the fasteners 23 and the lips 70 12. Thus the cover through its resilient connection with the bar 17 will be free to move relatively to the bar and receptacle while the cooking operation proceeds either to move upward under expansion of the meat 75 or downward in case there is contraction or shrinkage of the meat.

I claim:

1. The combination of a receptacle having an outwardly formed stiffening flange 80 at its upper portion, portions of the flange being deflected downward forming engagement lips, a cover for the receptacle, and members carried by the cover and co-operating with the lips for holding the cover 85 in fixed relation to the receptacle.

2. The combination as set forth in claim 1 wherein the members for fastening the cover comprise racks formed of sheet metal, the teeth of the racks being struck inward 90 from the main portion thereof remote from the edges and directed upward to selectively engage with the lip portions of the flange.

3. The combination with a receptacle whose upper portion is outwardly flanged and portions of the flange being bent downward forming lips, of a cover for the receptacle, a bar connected to the cover and extending beyond the ends thereof, and a pair of racks pivoted to the ends of the 100 bar and co-operating with said lips of the receptacle respectively.

4. A corned beef cooker comprising, in combination, a receptacle having formed along its longitudinal center an integral 105 flat partition having its upper free edge tapered and sharpened and lying substantially in a horizontal plane close above the vertical center of the receptacle, and a cover having a depending marginal flange movable downward within the receptacle toward said receptacle partition and having an integral partition projecting downward below the flange aforesaid and into close gliding contact with either side of the first mentioned partition, the cover partition having its free edge beveled to facilitate its gliding co-operation along the receptacle partition and constituting a wedge which when withdrawn with the cover relieves the beef mass 115 120 adjacent thereto to facilitate the delivery thereof.

5. In a corned beef cooker, the combination of a receptacle whose two ends are similarly formed and having a vertical partition 125 along its longitudinal center dividing the receptacle into two equal compartments for forming two cooked masses of substantially equal size, the upper edge of the partition being beveled and located materially below 130

the top of the receptacle, a cover conforming to and movable downward within the receptacle toward the aforesaid partition and having a partition depending therefrom 5 well below all other portions of the cover, the cover partition having its lower edge beveled for easy sliding and overlapping co-operation with either side of the receptacle partition irrespective of how the cover is introduced into the receptacle, and means ¹⁰ to secure the receptacle and cover in molding co-operation with each other.

In testimony whereof I affix my signature.
HANS ADELMANN.
